(57) CLAIM

The ornamental design for a portable game device with LCD, as shown and described.

DESCRIPTION

FIG. 1 is a front view of a portable game device with LCD showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a view thereof, with the cases being shown in the rotated position; and,

FIG. 8 is a perspective view thereof.

The broken lines are for illustrative purpose and form no part of the claimed design.
